(57) **CLAIM**

The ornamental design for a corrugated display cart, substantially, as shown and described.

DESCRIPTION

FIG. 1 is a top, left end and right side perspective view of a corrugated display cart showing my new design the dotted lines being for reference only;

FIG. 2 is a top plan view thereof;

FIG. 3 is an end elevational view thereof;

FIG. 4 is a bottom plan view thereof;

FIG. 5 is a side elevational view thereof;

FIG. 6 is an end elevational view of an alternative form of cart;

FIG. 7 is a bottom plan view thereof; and,

FIG. 8 is a side elevational view thereof.

The broken line showing of castors and internal structure is for illustrative purposes only and forms no part of the claimed design.
